United States Patent Office

Des. 221,955
Patented Sept. 21, 1971

221,955

LASER OR SIMILAR APPARATUS

Edward D. Lucey, Los Gatos, Calif., assignor to
Sylvania Electric Products, Inc.

Filed May 4, 1970, Ser. No. 22,989

Term of patent 14 years

Int. Cl. D14—04

U.S. Cl. D26—14

FIG. 1

FIG. 2

Des. 221,955

PAGE 2

FIG. 5

FIG. 1 is a perspective view of a laser or similar apparatus showing my design;

FIG. 2 is a front view thereof;

FIG. 3 is a side view thereof;

FIG. 4 is a rear view thereof, the view being taken on line 4—4 of FIG. 3;

FIG. 5 is a top view thereof, the view being taken on line 5—5 of FIG. 3.

I claim:

The ornamental design for a laser or similar apparatus, as shown.
